ROBERT H. PLASS, OF UPPER MONTCLAIR, NEW JERSEY, ASSIGNOR TO THE DAISY PRODUCTS, INC., OF NEW YORK, N. Y., A CORPORATION OF NEW YORK.

MACHINE FOR APPLYING REINFORCEMENTS TO BAGS OR THE LIKE.

Application filed June 18, 1927. Serial No. 199,847.

This invention relates more particularly, but not necessarily, to machines for applying stiffening strips between the outer walls and linings of hand bags or the like, such, for example, as the well known form of drum shaped hat hand bags. With respect to hat hand bags considerable difficulty is experienced in inserting stiffening material, such as a strip of card-board, between the outer wall and the lining, especially where the lining has been already incorporated with and sewed into the bag. In such case usually a slit is provided in the lining and the stiffening or reenforcing strip inserted therethrough, sometimes in one piece and sometimes in two pieces.

One of the objects of the present invention has therefor specifically in view a machine which will insert or enable the insertion of a stiffening strip into hat hand bags, such as referred to, although the invention has a broader aspect, for it is capable of general use in the arts where stiffening or reenforcing material is to be applied to containers, bags, boxes, etc., whether the article be cylindrical, rectangular or some other shape.

Other objects of the invention are to provide efficient, economical and practical means for applying reenforcements to bags or the like, preferably in the form of a machine having a mandrel for receiving the article to which the reenforcement is to be applied.

These being among the objects of the present invention, the same consists of certain features of construction and combinations of parts to be hereinafter described and then pointed out in the claims, reference being had to the accompanying drawings illustrating a preferred embodiment of the invention, and in which:

Figure 1 is a sectional side elevation of the machine provided with power means for operating it;

Fig. 2 is an enlarged sectional side elevation of the mandrel and concomitant parts;

Fig. 3 is a vertical central section of the machine showing the parts in position at the end of the forward movement;

Fig. 4 is a section of some of the parts in the same position, taken at right angles to Fig. 3;

Fig. 5 is an elevation as viewed from the interior of the machine, partly in section, and showing a container or bag placed on the mandrel;

Fig. 6 is a transverse section showing how the guide nose for the strip of reenforcing material is placed with respect to the bag or container, and

Fig. 7 is a detail of the outer part of the guide-nose.

Referring to the drawings, a suitable supporting frame 10 is provided which receives a tubular support 11 held rigidly to the frame by a set-screw 12. Preferably the frame 10 is upright and the tubular support 11 horizontal, and on one end of the tubular support there is mounted a stationary head 13. The position of this head is not essential, except that it is preferred that it stand vertical at the end of the support 11.

The head 13 is fixed to the support 11 by means of a set-screw 14, and at the center of the head 13 there is fixed a pivot shaft 15 by means of a set-screw 16. On the other end of the shaft 15 a complementary head 17 is rigidly fixed by means of a set-screw 18.

As shown more clearly in Fig. 3 the two rigid heads 13, 17 are directly opposite one another, and are preferably of identical construction. Preferably the heads 13, 17 are formed conjointly in the outlines of a cylinder and they constitute a mandrel over which the bag or other article to be reinforced or stiffened may be placed.

As shown more clearly in Fig. 3 the rigid heads 13, 17 are respectively provided around their peripheries with guide-flanges 19, 20, the flange 19 being provided with a ring or plate portion 21 and the flange 20 with a similar portion 22, these ring or plate portions being rigidly fixed to opposite sides of the heads 13, 17 by means of counter-sunk set-screws 23. Generally, but not necessarily, the contour of each head 13, 17 is circular and in such case each guide-flange 19, 20 follows the circular contour and is spaced a slight distance away therefrom so as to provide opposite and concentric guide-ways 24, 24^a. These guide-ways open the one towards the other, that is, towards the central plane of the mandrel, so as to receive and guide a strip of flexible reinforcing material.

Each of the heads 13, 17 has cut into its peripheral portion a gap 25, and the two gaps are opposite each other. These two gaps will be referred to as one gap, as opposite the gap 25 there extends a guide-nose 26 from the guide-ways 24, 24^a. This guide-nose facilitates the leading of the strip of material to

the wall of the bag or container which is to be reinforced, and preferably the guide-nose 26 extends tangentially of the mandrel, if that be circular. In any event it preferably diverges slightly from the mandrel.

The guide-nose 26 preferably comprises inner metal blades 27, 28 and outer metal blades 29, 30, which are suitably rigidly fixed to the mandrel, to form between them a directional extension of the guide-ways 24, 24^a. While there are preferably four of these blades, producing a sort of duplex nose, the combined blades will be referred to herein as a guide-nose, the blades 27, 29 at one side being separated from the blades 28, 30 at the other side of the mandrel by the preferred special distance between the two heads 13, 17 of the mandrel.

Mounted in the tubular support 11 is a shaft 31 which may be employed as a shaft driven from a motor 32, as shown in Fig. 1. The motor shaft 33 is provided with a pinion 34 which meshes with a large gear-wheel 35 loosely mounted on the shaft 31. Opposing the gear-wheel 35 is a friction-disk 36 which is rigidly secured to the shaft 31 so that one face of the gear-wheel 35 may be brought in frictional contact with the friction-disk 36 by means of a helical pressure spring 37 fixed at one end to the shaft 31 and bearing at its other end upon a portion of the gear-wheel 35.

On the inner end of the shaft 31 there is fixed a pinion 38, which turns in a suitable recess in the mandrel head 13, and in the same recess there is arranged a large gear-wheel 39, with which pinion 38 meshes, and which is mounted loosely on the mandrel shaft 15. A large ratchet wheel 40 is firmly attached to one face of the gear 39, while between the ratchet wheel 40 and the other mandrel head 17 there is loosely placed upon the shaft 15 a sleeve or hub 41 of an arm 42. A sweeping motion may be produced on the arm 42 so as to move it around the pivot shaft 15 and between the heads 13, 17.

A pawl 43 is pivoted to the swinging arm 42 intermediately of the length thereof, and the toe of the pawl is adapted to engage the teeth of the ratchet wheel 40. A spring 44 fixed to the arm 42 at one end bears at its opposite end upon the toe portion of the pawl 42 with a view to forcing the toe of the pawl into engagement with the ratchet teeth.

Grasping means 45 are located at the outer end of the arm 42, the same extending laterally of the arm. Such means 45 are adapted to engage one end of a strip 46 of reinforcing material, as card-board, for example, and such grasping means preferably comprise a fixed jaw 47 extending rigidly from the arm 42 and a movable jaw 48 which opposes the said fixed jaw. The movable jaw 48 is mounted on a pivot pin 49 on the arm and is provided with a heel-member 50 (shown clearly in Fig. 4), between which heel and a suitable seat of the

arm 42 an expansion spring 51 is arranged, the tendency of which is to close the jaw 48 towards the jaw 47 and to grasp or grip the reinforcing material 46. The jaw 48 is also provided with a finger-piece 52 constituting manual means for opening the jaw 48 in opposition to the expansion spring 51.

The described machine is adapted for either power operation or manual operation. The power operation thereof will first be described. When it is desired, for example, to apply reinforcing material to a bag 53, usually composed of flexible material, the bag is placed over the mandrel 13, 17, as shown more clearly in Fig. 5. If a hat hand bag of a certain construction is to be reinforced it would have a peripheral wall or band portion 54 of leather or leather-like material and a lining 55 of thin textile material to give an interior finish to the bag. After the fabric lining 55 has been incorporated with the bag and sewed into its material, it is usually not an easy matter to insert stiffening material in the form of a strip 46 between the outer wall 54 of the bag and the lining 55. In such a case a transverse slit is left or made in the lining 55, as defined by the edges 56, 57 of the slit (see the upper part of Fig. 5). Before placing the bag on the mandrel a strip of stiffening material 46 is easily threaded into the guide-ways 24, 24^a around the mandrel until the forward end thereof is within the guide-nose 26, the rear end thereof being in position to be engaged or grasped by the jaws 47, 48, which are caused to engage the material as shown in Fig. 5. The bag to be reinforced having been placed over the mandrel, it is so positioned as to enable the guide-nose 26, with the end of the material 46 held thereby, to be inserted through the slit in the lining at 56, 57, so that the slit will be positioned adjacent the base of the guide-nose, with the forward end of the material inserted between the wall 54 and the lining 55 of the bag.

The operator now takes firm hold of the bag and sets the motor 32 in operation. The shaft 31 will now be driven, which will cause the intermeshing pinion 38 and gear 39 to rotate the ratchet wheel 40 in the direction of the arrow, Fig. 5, thereby pushing the stiffening strip 46 along the guide-ways 24, 24^a and through the guide-nose 26, and while the operator is holding the bag, the strip will be fed continuously between the outer wall 54 and the lining 55 of the bag. It will be seen that the ratchet wheel 40 at this time is in constant engagement with the pawl 43 and causes the arm 42 to sweep around shaft 15 with a continuous progressive pushing or feeding action.

Means are provided for stopping the advancing movement of the arm 42, and hence the strip 46 and also means for disengaging the strip 46 from the jaws 47, 48 when the strip has advanced as far as desired. Such

means preferably work automatically and will now be described. A cross-piece 58 at one end of the transverse gap 25 in the mandrel is attached to its opposite ends to the 5 heads 13, 17, as shown more clearly in Figs. 1 and 3. This cross-piece constitutes a forward stop for the arm 42 and also means for opening the jaws 47, 48. It will be seen from Fig. 4 that when the arm 42 reaches the end 10 of its forward movement it abuts against the stop 58, and simultaneously the said stop bears on the heel-member 50 of the movable jaw 48 and compresses the spring 51, thereby opening the jaws 47, 48 and releasing the reinforcing strip 46 therefrom. The entire strip will then be inserted between the outer wall and the lining of the bag, and the machine may then be set so as to start all over again and feed another strip through the 20 same slit in the bag, but in contrary direction to the strip first inserted.

When the arm 42 reaches the end of its forward movement as restricted by a stop 58, a lateral shoulder or projection 60 on the rear 25 end of the pawl 43 is brought into engagement with a release pin 59 which is inserted in a hole in the head 13 so as to have a fixed position, although such pin is removable. This abutment against the pin 59 disengages 30 the toe of the pawl 43 from the teeth of the ratchet 40, and as the material 46 has been released from the jaws and the pawl 43 disengaged from the ratchet, the arm 42 and concomitant parts may be returned to rearward 35 position. However, the rear end of the pawl 43 is provided with a notch 61 into which snaps the bent end 62 of a plate spring 63 fixed to the swinging arm, which snapping engagement is brought about by the outward 40 movement of the pawl caused by the release pin 59. The plate spring 63 maintains the pawl 43 disengaged from the ratchet until the arm 42 is moved by hand back to starting 45 position. At the starting position, the head 13 is provided with a throw-pin or back-stop 64 inserted through a hole in said head, and which engages the toe of the pawl 43 when the arm has been returned to its original or starting position. This acts to reengage the 50 toe of the pawl 43 with the teeth of the ratchet 40, and the same also disengages the end of the plate-spring 63 from the notch in the pawl, all as shown in Fig. 5. Another reenforcing strip may now be placed on the mandrel and attached to the jaws of arm 42 for the forward movement of such strip. The head 13 may be provided with a series of holes 65 for a different positioning of the throw-pin or back-stop 64, for a shorter forward movement of the arm 42, for inserting shorter lengths of stiffening or reenforcing material.

Preferably the head 13 is provided with two or more holes 66, 67 and head 17 is provided with similar, coinciding holes 68, 69.

It will be seen that when the tubular support 11 is entered into the hole 66 and the head 13 rigidly fixed to said support, that larger bags may be accommodated on the mandrel than when the tubular support 11 is fixed in the 70 hole 67. When support 11 is fixed in hole 67 the machine may be only operated by hand for stiffening smaller bags. In that case longer screws 70 are used to connect gear 39 and ratchet 40, and these are screwed into 75 suitable holes in head or frame 13 to hold the gear and ratchet rigidly. The holes 68, 69 are provided in head or frame 17 so that the machine may be made left handed by fixing support 11 in either of them. As shown in 80 the drawings the machine is right handed.

When the support 11 is fixed in either hole 66 or 68, and, if then, the stiffening or reenforcing material is to be applied by hand, that is without the use of the motor 32, it is necessary to tighten up the set-screws 71, shown in Fig. 1, against the shaft 31, as shown in Fig. 3, thereby holding shaft 31 rigidly within the tubular support 11. This fixation of shaft 31 will also hold the gears 38, 39 and 85 the ratchet wheel 40 stationary. To insert a stiffening strip 46 by hand, the operator grasps one end of the strip 46 by the jaws of the arm 42, after the strip has been threaded into the guide-ways of the mandrel, and 90 places the bag upon the mandrel so as to insert the other end of the strip and the guide-nose 26 through the slit in the lining of the bag. He now takes hold of the bag and lining at a point opposite the nose 26 and pulls the 95 material 26 for a short distance through the guide-nose, and then moves the bag back a similar distance, and continues this manipulation step by step until the stiffening strip 46 is fed by a step by step movement through 100 between the wall 54 and the lining 55 of the bag. In some cases this hand method is desirable, although ordinarily speaking the power method is better, because quicker and more expeditious in turning out the work. 105 It will be seen that as the operator feeds the strip 46 forward step by step that the strip pulls the arm 42 around and the toe of the pawl 43 rides idly over the teeth of the ratchet wheel 40. The toe of the pawl by engagement 110 with the ratchet teeth will prevent retrograde movement of the stiffening strip 46. When the arm 42 reaches the end of its step by step advance movement, the operation to automatically disengage the pawl from the ratchet, to disengage the grasping arms 47, 48 from the strip, etc., are the same as when motor power is used.

It is obvious that the described and illustrated invention is susceptible to a wide range 115 of modification without departing from the spirit of the invention as expressed by the scope of the appended claims.

What I claim as new, is:

1. In a machine of the class described, the 120

- combination of means for supporting a receptacle, means for grasping a length of stiff material and which is locatable in the receptacle, means for advancing the grasping means relatively to an inner wall of the receptacle and for moving the strip along the wall, and means for releasing the grasping means at a predetermined distance of advance.
2. In a machine of the class described, the combination of means for supporting a receptacle, means for grasping a length of stiff material, a guide-nose for one end of the material and for entering within the supported receptacle, means for advancing the grasping means to feed the material through the guide nose relatively to an inner wall of the receptacle and for moving the strip along the wall, and means for releasing the grasping means.
3. In a machine of the class described, the combination of means for supporting a receptacle, means for engaging a length of stiff material, means for guiding the material within the supported receptacle, means for advancing the engaging means along the guiding means, and means permitting the feed of material for a definite distance.
4. In a machine of the class described, the combination of means for supporting a receptacle, means for engaging a length of stiff material, means for guiding the material within the supported receptacle, a guide-nose for the protrusion of the material, means for advancing the engaging means along the guiding means and the guide-nose, and means permitting the feed of material for a definite distance.
5. In a machine of the class described, the combination of means for supporting a receptacle, means for grasping a length of stiff material and which is locatable in the receptacle, a pawl and ratchet for advancing the grasping means relatively to an inner wall of the receptacle and for moving the strip along the wall, and means for disengaging the pawl from the ratchet at the completion of the advance.
6. In a machine of the class described, the combination of means for grasping a length of stiff material, a pawl and ratchet for advancing the grasping means, means for releasing the grasping means when desired, and means for disengaging the pawl from the ratchet at the completion of the advance.
7. In a machine of the class described, the combination of means for grasping a length of stiff material, means for guiding the material, a guide-nose at the end of the guiding means, pawl and ratchet means for advancing the grasping means and for preventing retrograde movement of the material, and means for simultaneously releasing the grasping means from the material and the pawl from the ratchet at the end of the advance of the material.
8. In a machine of the class described, the combination of means for grasping a length of stiff material, means for guiding the material, a guide-nose at the end of the guiding means, pawl and ratchet means for advancing the grasping means and for preventing retrograde movement of the material, means for simultaneously releasing the grasping means from the material and the pawl from the ratchet at the end of the advance of the material, and means for causing the releasing means and the pawl and ratchet to assume normal position on a backward movement.
9. In a machine of the class described, the combination of guiding means for a length of stiff material, such means extending in a loop, means for engaging such material, and movable along the guiding means in an advancing direction, means for producing the advance, and means for disengaging the material from the engaging means when advanced a definite distance.
10. In a machine of the class described, the combination of guiding means for a length of stiff material, such means extending in a loop, means for engaging such material, and movable along the guiding means in an advancing direction, a guide-nose for the protrusion of the material from the guiding means, means for producing the advance, and means for disengaging the material from the engaging means when advanced a definite distance through the guide nose.
11. In a machine of the class described, the combination of guiding means for a length of stiff material, such means extending in a loop, means for engaging such material, and movable along the guiding means in an advancing direction, a pawl and ratchet device constituting means for producing the advance, and means for disengaging the material from the engaging means when advanced a definite distance.
12. In a machine of the class described, the combination of guiding means for a length of material, such means extending in a loop, and a guide nose by which the material may be led from the guiding means.
13. In a machine of the class described, the combination of guiding means for a length of material, such means extending in a loop containing a gap, and a guide nose at the gap and by which the material may be led from the guiding means.
14. In a machine of the class described, the combination of guiding means for a length of material, such means extending in a circular loop, and a guide nose extending tangentially of the circle and by which the material may be led from the guiding means.
15. In a machine of the class described, the combination of a mandrel for supporting an article to be reenforced, and guiding means for the reenforcing material and extending around the mandrel and provided with means

- for directing a length of the material onto a wall of such article.
16. In a machine of the class described, the combination of a mandrel for supporting an article to be reenforced and having a peripheral gap, and guiding means for the reenforcing material and extending around the mandrel, and provided with means terminating at the gap for directing a length of the material onto a wall of such article.
17. In a machine of the class described, the combination of a mandrel for supporting an article to be reinforced, and guiding means for the reenforcing material and extending around the mandrel, and provided with a guide-nose for directing a length of the material onto a wall of such article.
18. In a machine of the class described, the combination of a substantially cylindrical mandrel for supporting a cylindrical bag or the like to be reenforced, and guiding means for the reenforcing material and extending around the mandrel, and provided with means for directing a length of the material along a wall of such bag.
19. In a machine of the class described, the combination of two spaced heads constituting a mandrel and provided with guides extending around them, said guides serving to guide a strip of material, and a guide nose from the guides serving to direct the strip onto the wall of an article supported on the mandrel.
20. In a machine of the class described, the combination of two spaced heads constituting a mandrel and provided with guides extending around them, said guides serving to guide a strip of material, a guide nose from the guides serving to direct the strip onto the wall of an article supported on the mandrel, strip grasping means movable between the heads, and means for assuring a forward advance of the grasping means.
21. In a machine of the class described, the combination of guiding means for a length of stiff material, such means extending in a loop, and a guide nose by which the material may be led from the guiding means, an arm provided with means for pushing such material, a pivot for the arm, and a pawl and ratchet device operating to swing the arm about the axis of said pivot.
22. In a machine of the class described, the combination of guiding means for a length of stiff material, such means extending in a loop, and a guide nose by which the material may be led from the guiding means, an arm provided with means for pushing such material, a pivot for the arm, and means operating to swing the arm forwardly about the axis of the pivot, and a stop to limit the forward movement of the arm.
23. In a machine of the class described, the combination of guiding means for a length of stiff material, such means extending in a
- loop, and a guide nose by which the material may be led from the guiding means, an arm provided with means for pushing such material, a pivot for the arm, and means operating to swing the arm forwardly about the axis of the pivot, a stop to limit the forward movement of the arm, and means operating to swing the arm forwardly about the axis of the pivot, a stop to limit the forward movement of the arm, and means operating to swing the arm forwardly about the axis of the pivot, a stop to limit the forward movement of the arm.
24. In a machine of the class described, the combination of a mandrel for supporting an article to be reenforced, guiding means for stiff reenforcing material and extending around the mandrel, and provided with means for directing a length of the material onto a wall of such article, a swingable arm provided with means for pushing such material, such arm mounted within the mandrel, and means operating to swing the arm forwardly.
25. In a machine of the class described, the combination of a stationary mandrel for supporting an article to be reenforced, guiding means for stiff reenforcing material and extending around the mandrel, and having means for directing a length of the material onto a wall of such article, a shaft mounted within the mandrel, a ratchet wheel loose on the shaft, an arm for feeding the material and pivoted on the shaft, and having a pawl to engage the ratchet, and power means to turn the ratchet whereby to advance the arm.
26. In a machine of the class described, the combination of a stationary mandrel for supporting an article to be reenforced, guiding means for stiff reenforcing material and extending around the mandrel, and having means for directing a length of the material onto a wall of such article, a shaft mounted within the mandrel, a ratchet wheel loose on the shaft, an arm for feeding the material and pivoted on the shaft, and having a pawl to engage the ratchet, power means to turn the ratchet whereby to advance the arm, means to automatically disengage the pawl from the ratchet when the arm has advanced to the end of its movement, and means to automatically reengage the pawl with the ratchet on a return movement of the arm.
27. In a machine of the class described, the combination of a stationary mandrel for supporting an article to be reenforced, guiding means for stiff reenforcing material and extending around the mandrel, and having means for directing a length of the material onto a wall of such article, a shaft mounted within the mandrel, a ratchet wheel loose on the shaft, an arm for feeding the material and pivoted on the shaft, and having a pawl to engage the ratchet, power means to turn the ratchet whereby to advance the arm, means on the arm for grasping the material to feed it forwardly, and means for disengaging the grasping means when the arm has advanced to the end of its movement.

ROBERT H. PLASS.
